UNITED STATES PATENT OFFICE.

JOHN E. SMITH, OF NEW YORK, N. Y., ASSIGNOR TO THE GOLD AND STOCK TELEGRAPH COMPANY, OF SAME PLACE.

CIRCUIT-CONTROLLER FOR ELECTRIC CLOCKS ON TELEPHONE AND OTHER LINES.

SPECIFICATION forming part of Letters Patent No. 309,001, dated December 9, 1884.

Application filed March 29, 1883. (No model.)

To all whom it may concern:

Be it known that I, JOHN E. SMITH, of the city, county, and State of New York, have invented a new and useful improvement in apparatus for controlling electric circuits which are used both for controlling clocks and for operating telephonic or other lines or apparatus, of which the following is a specification, reference being had to the accompanying drawings.

In another application, Serial No. 89,786, filed on the same date herewith, I have described a method of and means for setting and synchronizing clocks connected with electric circuits primarily and ordinarily used for other purposes, and on which the usual currents are all of one polarity. In that method I employ polarized shunts which keep the usual currents diverted from the clocks until the moment arrives for their correction, when a reversed current, by its action on the shunts, lets the clocks into circuit, and if not indicating the right time puts them into unison with a standard-time piece.

My present invention is for the correction of clocks connected with circuits primarily used for other purposes, but on which currents of either the same polarity or opposite polarities do the usual work.

Briefly stated, it consists in the combination, with devices for setting clocks by electricity and other electrical apparatus, of non-polarized electro-magnetic shunts, which, during the ordinary use of the line or lines, keep the several clock-setting devices shunted, but bring them into circuit for synchronizing the clocks by the action of a re-enforcing or a stronger current than that employed to do the ordinary work of the line or lines.

Figure 1 in the drawings is a diagram showing my invention as applied to four similar circuits radiating from a central station from which the several clocks in such circuits are to be corrected. Fig. 2 exhibits a modification of the method of applying the battery.

The apparatus at central station A necessary to be considered in connection with my invention is shown in Fig. 1, in which *a* is the switch-board, with which the several lines, *b b'* 50 *b'' b'''*, connect, and through which they also

connect with the earth or return-circuit *c* by means of a switch, *d*. The other end of each of these lines connects with the earth or return-circuit *c*, as is well understood. Each of the four divisions B B B B of the diagram 55 shows a clock, a shunt, and other electrical apparatus connected in a circuit in accordance with my invention. These four divisions being exactly alike, a description of one will describe all of them. Referring to either 60 of said divisions, *c* is a clock, *h* is telephonic or other apparatus operated by currents of any polarity, and *i* an electro-magnet of a non-polarized shunt, all situated in circuit *b*. The armature-lever *k*, when moved by the 65 magnet *i*, makes electrical contact with screw *l*, and like contact with screw *m* when moved by the retracting-spring *n*. A shunt of this description may be made by taking such a magnet as is commonly used for connecting 70 the main and the local circuits in the Morse telegraph and adding to it the electrical contact-screw *m*, and therefore I make no claim to such a shunting-instrument. A wire, *o*, connects armature-lever *k* with circuit *b* between clock *c* and the telephonic or other apparatus, *h*, wire *r* connects screws *m* to said circuit on the other side of said clock, and a third wire, *s*, joins screw *l* to said circuit at a point between magnet *i* and apparatus *h*. 75 Thus wires *o r* form a shunt-circuit to the magnet for operating the device for setting the clock *c*, while a shunt-circuit to apparatus *h* is formed by wires *o s*.

The correcting or setting devices applied to 80 the clock are the same as those fully described in my application No. 89,786, and to which reference has been hereinbefore made.

During the operation of apparatus *h*, and between the times at which the clock is to be 85 corrected, spring *n* must have sufficient tension to hold lever *k* against screw *m*, and thus keep the clock shunted, and at the same time, if apparatus *h* is a telephone or other instrument worked by magneto and not by voltaic 90 currents, switch *d* connects directly to the earth or return circuit *c*, as shown in plain lines in Fig. 1.

To correct the clock, the switch *d* or its equivalent is moved (by hand or by a standard- 95 100

time piece) to a position as shown by dotted lines, so as to bring into circuit *b* a battery, *t*, whose current is powerful enough to overcome the tension of spring *n*, and thus cause lever 5 *k* to close circuit *o s*, shunting apparatus *h*, and at the same time to break shunt-circuit *o r*, let clock *e* into circuit, and set it to correct time, as fully set forth in Case A.

When apparatus *h* is a printing-telegraph 10 or any other instrument operated by voltaic currents of any polarity, the switch, battery, and earth or return circuit should be arranged substantially as shown in Fig. 2. While such instrument is in use, the switch *d* connects circuits *b b' b'' b'''* to a portion of battery *t*, sufficient for its operation, and during such operation spring *n* must have tension enough to keep the clock shunted. When the clock is 15 to be corrected, switch *d* is moved to the position shown in dotted lines in Fig. 2. This movement connects the whole of battery *t* to said circuit, and the re-enforced current overcomes spring *n*, shunts the printer or other apparatus, and lets into circuit and corrects 20 the clock, as hereinbefore described.

Though I have shown but one set of apparatus in each circuit, it is evident that there may be several sets, and all simultaneously operated in the same manner. I will also point out 25 that if there should be but one shunt and one apparatus *h* in a building, several clocks in different parts of such building might be placed in that circuit and all of them corrected as one clock by the action of that one shunt. In such 30 a case one re-enforced current sufficient to operate the shunt might be sent through the circuit a second or two before the time for setting the clocks, and then at the exact hour a still stronger current sent to act on the clocks with 35 sufficient power to correct them.

It will be seen that by the use of shunts with soft-iron armatures, as herein described, and

operated by re-enforced currents, or currents stronger than those employed for the other uses of the circuits than that of setting clocks, 45 several main batteries may be used on such circuits.

The current for operating the shunts and setting the clocks may be augmented by shunting resistance from the line, as well as by the 50 addition of battery or increase of electro-motive force, and I regard such shunting of resistance from the line as equivalent to augmenting or re-enforcing the battery power thereon.

What I claim as my invention, and desire 55 to secure by Letters Patent, is—

1. The combination, with and directly in a main electric circuit of telegraphic, telephonic, or other apparatus, of an electro-magnet for setting a clock and a magnet for operating a 60 shunt for diverting the current from the clock-setting magnet or from the telegraphic, telephonic, or other apparatus, the shunting-lever being in a circuit which branches from the main circuit at a point between the clock-setting magnet and the telegraphic, telephonic, or other apparatus, substantially as herein 65 described.

2. The combination, with an electric circuit employed for telegraphic, telephonic, or other 70 uses, of a clock, a device for setting said clock, an electro-magnet in said circuit for operating said setting device, a non-polarized shunt for directing the current through said magnet or through said telegraphic, telephonic, or other 75 apparatus, a battery for producing a re-enforcing or stronger current than that used for the other uses than that of setting the clocks, and a switch for connecting said battery with the circuit, substantially as herein described.

JOHN E. SMITH.
